Primary Examiner — Ramzi S Almatrahi(74) Attorney, Agent, or Firm — Wayne & Ken, LLC;
 Tony Hom(57) **CLAIM**

The ornamental design for a baby monitor, as shown and described.

DESCRIPTION

FIG. 1 is a front perspective view of a baby monitor showing our new design;

FIG. 2 is a back perspective view thereof;

FIG. 3 is a front elevation view thereof;

FIG. 4 is a back elevation view thereof;

FIG. 5 is a left side view thereof;

FIG. 6 is a right side view thereof;

FIG. 7 is a top plan view thereof; and,

FIG. 8 is a bottom plan view thereof.

The broken lines depict portions of the baby monitor in which the design is embodied that form no part of the claimed design.
